US00D474252S

(12) **United States Design Patent** (10) Patent No.: **US D474,252 S**
Lull et al. (45) Date of Patent: ** May 6, 2003

(54) **EXERCISE BICYCLE FRAME**

(75) Inventors: **Andrew P. Lull**, Boulder, CO (US);
William A. Baker, Longmont, CO (US); **Douglas J. Golenz**, Lafayette, CO (US)

(73) Assignee: **Nutilus, Inc.**, Louisville, CO (US)

(**) Term: **14 Years**

(21) Appl. No.: **29/156,792**

(22) Filed: **Mar. 6, 2002**

(74) *Attorney, Agent, or Firm*—Dorsey & Whitney LLP

CLAIM

The ornamental design for an exercise bicycle frame, as shown and described.

DESCRIPTION

FIG. 1 is a perspective view of the exercise bicycle frame of the present invention;
FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof; and,
FIG. 7 is a bottom plan view thereof.
